UNITED STATES PATENT OFFICE

CARLTON L. HOFF AND THOMAS P. LONG, OF YORK, PENNSYLVANIA; SAID LONG
ASSIGNOR TO SAID HOFF

TURBINE

Application filed August 16, 1928. Serial No. 300,054.

This invention relates to improvements in turbines and while it has been developed for use with water as motive fluid, other fluids such as air or steam may be utilized in lieu 5 of water.

Primarily, the object contemplated is the increase in efficiency of the turbine while, at the same time, the construction thereof is not complicated but is one that can be produced 10 from a comparatively small number of parts of simple design and sturdy construction, whereby the turbine will possess great durability.

More specifically, the invention contemplates a turbine embodying an enclosed shaft having a spiral blade thereon whose pitch decreases from the inlet for the motive fluid toward the outlet therefor, there also being means for causing the motive fluid to impinge 15 on said blade at points gradually receding from the center of rotation of said shaft as said fluid passes toward the end of the blade of decreased pitch. In this manner, the force of the motive fluid is exerted on the blade at 20 points farther from the center of rotation of the shaft at the time said fluid exerts the greatest pressure on said blade, due to the decreased pitch of the latter. This, in effect, increases the leverage of the blade, with respect to its center of rotation or the shaft 25 on which it is mounted, thereby increasing the efficiency of the turbine.

A further object is the provision of a special head for delivering the motive fluid to the blade so as to further increase the efficiency of the turbine.

With these and other objects in view, the invention consists in certain novel details 35 of construction and combinations and arrangements of parts, all as will hereinafter be more fully described and the novel features thereof particularly pointed out in the appended claims.

45 In the accompanying drawings,

Figure 1 is a plan view of a turbine embodying the present improvements;

Fig. 2 is a view taken at right angles to Fig. 1 and partly in section to show the interior of the casing;

Fig. 3 is a detail plan view of the head for the inlet of the casing;

Fig. 4 is a view, partly in section, illustrating a modified form of the invention;

Fig. 5 is a longitudinal sectional view of a 55 modified form of inlet head; and

Fig. 6 is a plan view of the inlet head shown in Fig. 5.

In the form of apparatus illustrated in Figs. 1 to 3, the turbine casing 10 is supported in a frame 11 which also affords bearings for the shaft 12 to be driven, said shaft carrying a gear 30 or other means for transmitting power generated by the turbine to any desired point or apparatus. 60

Within casing 10, shaft 12 is enlarged and tapered with its smaller extremity 14 located at the inlet end of casing 10, and its larger end 15 at the outlet end of said casing. At this end, casing 10 communicates with a 70 chamber 16 from which the motive fluid is discharged through a pipe 17. Fast on this tapered portion of shaft 12, is a spiral blade or vane 18 preferably, but not necessarily, extending unbroken the full length of casing 10. A continuous blade is preferred as greater efficiency is obtained. 75

In accordance with the present invention, the pitch of blade 18 is gradually reduced toward the discharge end of casing 10 or toward the larger extremity of tapered portion of shaft 12. At the smaller or inlet end of said shaft, there is a head 19 formed with a plurality of ports which cause the motive fluid entering the inlet end of casing 10 to 80 take a spiral path. The head 19 shown in Figs. 2 and 3 is a fixed one, the walls of the ports 20 therein being disposed at an angle to direct the motive fluid passing therethrough into a spiral path into the casing. 85

With the construction described, motive fluid, which may be either water, gas or steam, under suitable pressure, is delivered to casing 10 through ports 20 and impinges against blade 18 as it passes through said casing. Due to the reduced pitch of the blade toward the discharge end, greater resistance is offered to the movement of such motive fluid at this point and, as a consequence, greater pressure of force is imposed on that 90 95 100

portion of said blade. As has been described, as the pitch of said blade decreases, the diameter of shaft 12 increases and as a result, the force of the motive fluid is exerted on the blade at a point spaced radially further from the shaft or center of rotation of the blade. This, in effect, gives a greater leverage on the shaft thereby increasing the rotative force imposed thereon, and, as a result, the efficiency of the turbine is greatly increased.

In this form of the invention casing 10, which is cylindrical and of uniform cross section throughout its length, is fast in frame 11, the shaft being the rotatable element. Blade 18 is, therefore, carried by the shaft as described but it will be apparent that either the shaft or the casing may be the rotative element carrying said blade. To prevent leakage, shaft 12 is provided with a packing gland 21 at the point where it projects through chamber 16.

Instead of having a true cylindrical casing, the same may be tapered as shown at 30 in Fig. 4, to conform to the tapered portion of shaft 31. In this modification, the blade 32 is gradually reduced in pitch toward the larger end of the tapered shaft.

Figs. 5 and 6 illustrate a modified form of inlet head wherein there is a housing 34 adapted to be attached to the inlet end of the turbine casing in lieu of head 19 shown in Fig. 2. Within said housing is a sleeve 35 having in its interior a spider 36 whose arms 37 form a plurality of ports 38, the surfaces of said arms 37 being so disposed as to cause the motive fluid passing through said ports to be directed spirally into the turbine casing the same as in the construction shown in Figs. 1 to 3. Formed in housing 34 is an inlet 39 which communicates with a passage 40 between sleeve 35 and the interior surface of said housing. Passage 40 is gradually reduced in width around said sleeve and the latter is provided with a plurality of ports 41 whose walls are at a tangent to the periphery of the sleeve. Motive fluid entering port 39 enters the various ports 41 and in passing through ports 38 formed by the arms of spider 36 will take a spiral course entering the casing of the turbine. It will be understood that this form of head may be used with either form of turbine shown in Figs. 1 to 4.

What I claim is:

1. In a fluid current motor, the combination of a casing having inlet and outlet openings, a tapered shaft in said casing between said openings with its end of major diameter toward said outlet, a spiral blade encircling said shaft, the pitch of said blade decreasing toward said outlet, and means for directing a motive fluid in a spiral path against said blade at said inlet opening.

2. In a fluid current motor, the combina-

tion of a casing circular in cross-section and having inlet and outlet openings, a head at said inlet having ports therein disposed spirally of said casing, a shaft intermediate said inlet and outlet openings, a spiral blade 70 having a series of convolutions encircling said shaft, the pitch of said blade being gradually decreased toward said outlet, and means for gradually directing motive fluid 75 passing through the ports of said head toward the periphery of said blade and away from the center of rotation of said shaft.

3. In a fluid current motor, the combination of a casing circular in cross-section and having inlet and outlet openings, a head at 80 said inlet having ports therein disposed spirally of said casing, a shaft intermediate said inlet and outlet openings, a spiral blade composed of a series of convolutions encircling said shaft, the pitch of said blade being gradually decreased toward said outlet, said shaft being tapered toward said head whereby motive fluid entering the casing through said head will be directed toward 85 the periphery of said blade and away from the center of rotation of said shaft as it passes through said casing.
